UNITED STATES PATENT OFFICE.

CHARLES W. MABEY, OF INDIANAPOLIS, INDIANA.

SWITCH FOR ELECTRIC FLATIRONS.

1,410,262.

Specification of Letters Patent. Patented Mar. 21, 1922.

Application filed March 24, 1919. Serial No. 284,525.

To all whom it may concern:

Be it known that I, CHARLES W. MABEY, a citizen of the United States, residing at Indianapolis, in the county of Marion and State of Indiana, have invented certain new and useful Improvements in Switches for Electric Flatirons, of which the following is a specification:

This invention relates to a handle for electric flat-irons; and one of the objects of the invention consists in the provision of a handle of the above character whereby the electric circuit through the iron is completed when the operator grasps the handle and in which the circuit is broken when the operator loosens his or her grip on the handle, so that the possibility of the iron becoming over heated and starting accidental fires when not in active use is eliminated.

20 A further object of the invention consists in the provision of certain means whereby the electric circuit through the iron can be established and maintained for an indefinite period of time to initially 25 raise the temperature of the iron to the desired point without the constant attendance of the operator.

I accomplish the above objects of the invention, and such others as may appear 30 from a perusal of the following description and claims, by means of the construction illustrated in the accompanying drawings, forming a part hereof, in which—

Figure 1 is a side elevation of a conventional style of an electrically heated flat-iron, having my invention incorporated therein. Fig. 2 is a view through the longitudinal center of the handle, on an enlarged scale, showing the location and relative positions of the parts comprising my invention. Fig. 3 is a transverse sectional view, on the line 3—3 in Fig. 2. Fig. 4 is an end view of the handle, on the line 4—4 in Fig. 2.

45 Referring to the drawings, 10 represents the flat-iron and 11 a U-shaped support between the upright free ends 12 and 13 of which the handle is mounted a fixed distance above the iron 10. The handle for 50 the iron may be composed of fiber, rubber, wood or other suitable material, and is preferably formed in halves comprising the sections 14 and 15 to reduce the cost of manufacture, since the internal recesses, for imparting the necessary clearance for metal

core and the working parts, are more easily formed in the sections than would be possible in a single piece of material.

The core of the handle comprises a metal bar 18 which is recessed and shaped to form 60 a mounting for the movable parts. One end of bar 18 terminates in a vertically disposed hook 19 which is passed through a slot 20 in the end of upright 12 of a U-shaped support 11, whereby a loose pivotal 65 connection is formed to allow free vertical movement of the opposite end of the handle. The movable end of the handle is arranged so that the end of bar 18 rides against the inner face of upright 13 of 70 support 11, whereby a metallic connection is effected between the upright ends 12 and 13 of support 11 and flat-iron 10. Upright 13 is provided in its edges with marginal recesses 21 to form shoulders 22 and 75 23 which come into contact with a cross-bar 25 and limit both the upward travel of the handle and accidental separation of the parts.

Through the movability of one end of the 80 handle the electric circuit is established or broken and as the electric circuit is normally open when the iron is out of use the electric circuit is kept open by holding the movable end of the handle in its elevated 85 position through the medium of a spring 30 which bears at its upper end against bar 18 and its lower end resting upon shoulders 31 formed in a fiber block 32 which is secured to upright 13 by means of screws 33. 90 Spring 30 surrounds a pin 34 which is connected to bar 18 and the lower end of the pin terminates in a square enlargement 35 which forms a part of a switch by which the electric circuit through iron 10 is established or broken. The two sections 34 and 34^a forming the pin are rigidly secured together by means of the transverse pins 34^b. When the operator grasps the handle the latter is depressed, thereby moving enlargement 35 between the opposing faces of blades 36 of the switch and closing the electric circuit. Blades 36 are insulated by fiber block 32 and by connecting conductor wire 38 with one of said rivets and connecting the other rivet with iron 10 by means of the wire 38^a, and connecting conductor wire 39 directly with iron 10 a circuit is established through the latter. When the operator releases the handle the latter is 100 105 110

2
elevated under the influence of spring 30 and the electric circuit is broken.

To effect a positive connection between the movable end of the handle and upright 13 of support 11, and to prevent breaking of the electric circuit when the operator lifts the iron bodily from the ironing board, I provide upright 13 of support 11 with an aperture 40 into which a spherical ball 41 is slightly projected when the ball and aperture are brought into registration. This connection is effected by housing the ball 41 in a recess 42 in the end of bar 18 and subjecting said ball to forced movement toward upright 13 through the medium of a pin 44 which is actuated by a hand actuator lever 45 when the operator grasps the handle of the iron. As the operator depresses the handle lever 45 moves on its pivot 46 into the handle at which time the forward end 47 of lever 45 moves pin 44 longitudinally, thereby forcing ball 41 outwardly and into aperture 40 in upright 13 when the two register. As long as the operator maintains a firm grasp on the handle a permanent connection between the handle and upright 13 is maintained, but as soon as the operator releases the handle spring 48 returns hand actuator lever 45 to normal and releases ball 41, the latter moving backwards away from upright 13 as the handle is elevated under the influence of spring 30. Spring 48 is held against displacement by means of a lug 49 passing through the coil of said spring.

With the above description in mind, it will be observed that when the operator depresses the handle to cause enlargement 35 to contact blades 36 the electric circuit is established through iron 10, and when the operator's grip is relaxed the handle is moved under the influence of spring 30 to cause disengagement of the parts and break the circuit, thereby removing the possible danger of overheating iron 10 and starting accidental fires, resulting from carelessness on the part of the operator in failing to turn off the electric current when through ironing, or when called to perform some temporary duty, as frequently happens with electrically heated flat-irons at present upon the market.

As a convenience, and to remove the necessity of the presence of the operator during the time required in initially heating the iron to the desired temperature, I provide means consisting of a movable locking-lever 50 which normally reclines in a recess 51 cut into the adjacent wall of handle member 15. Lever 50 terminates in a cam 52 formed around the pivot 53 and when the lever is elevated, after the hand actuator lever is moved into the handle, cam 52 will bear upon and keep the forward end 47 of lever 45 depressed. By means of this construction

the operator may depress the handle and actuate lever 45 to keep the switch closed, thereby maintaining a closed circuit while iron 10 is initially being heated.

It will be understood that the various metal parts will be insulated as in common practice in the electrical art, so as to safeguard the operator against accidental shocks.

Having thus fully described my said invention, what I desire to secure by Letters Patent, is—

1. The combination with an electrically heated flatiron, of a pair of handle supporting uprights secured to said iron, a handle arranged between the free ends of the uprights, means pivotally connecting one end of the handle to the free end of one of said uprights, a pair of conductor wires, a circuit breaker arranged in the electric circuit, means carried by the movable end of the handle for engaging the circuit breaker with the handle depressed, means for normally holding the handle in its elevated position, and means preventing accidental separation of the movable end of the handle and the adjacent upright. 80

2. The combination with an electrically heated flatiron, of a pair of handle supporting uprights secured to said iron, a handle pivotally connected at one end to the free end of one of said uprights, a lever arranged in said handle and actuated by the grip of the operator, and means actuated by said lever for connecting the movable end of the handle with the adjacent upright when the handle occupies a depressed position. 95

3. The combination with an electrically heated flatiron, of a pair of handle supporting uprights secured to said iron, a handle pivotally connected at one end to the free end of one of said uprights, a lever arranged in said handle and actuated by the grip of the operator, means actuated by said lever for connecting the movable end of the handle with the adjacent upright when the handle occupies a depressed position, and means for holding the lever in its actuated position at the will of the operator. 105

4. The combination with an electrically heated flatiron, of a pair of handle supporting uprights secured to said iron, an insulating handle, a metallic core extending through said insulating handle and pivotally engaging the free end of one of said uprights, a ball arranged in the movable end of the core, a pin for moving said ball towards the free end of the adjacent upright, and a lever pivotally arranged in the handle and actuated by the grip of the operator for moving said pin and ball longitudinally. 115

5. The combination with an electrically heated flatiron, of a pair of handle supporting uprights secured to said iron, an insulating handle, a metallic core extending through said insulating handle and pivot- 120

ally engaging the free end of one of said uprights, a ball arranged in the movable end of the core, a pin for moving said ball towards the free end of the adjacent upright, a lever pivotally arranged in the handle and actuated by the grip of the operator for moving said pin and ball longitudinally, and means for holding said lever in an actuated position.

In witness whereof, I have hereunto set my hand and seal at Indianapolis, Indiana, this 10th day of March A. D. one thousand nine hundred and nineteen.

CHARLES W. MABEY. [L. S.]
